UNITED STATES PATENT OFFICE

FRANK A. FAHRENWALD, OF CHICAGO, ILLINOIS

FURNACE

Application filed February 19, 1929. Serial No. 341,178.

This invention relates to furnaces for heat-treating metal strips, sheets, plates, bars, packs and other articles and has particular relation to furnaces of the continuous process type wherein the articles operated upon are conveyed mechanically through at least the heated zone, and preferably also the cooling zones, on suitable rollers which are thus exposed to the full effect of the furnace. In my Patent No. 1,623,469, issued April 5, 1927, I described and claimed a fundamentally new type of furnace roll for use in apparatus of this kind wherein the rolls, instead of being cooled by a circulating fluid as theretofore, were allowed to assume the full furnace temperature, being made with reference to certain essential features of construction to enable the maintenance of rigidity despite the weakening of the metal due to the high temperature and by which the conveyance of heat along the metal towards the bearings was diminished to an amount which the bearings could successfully dissipate. The objects of the present invention are the provision of an other type of furnace roll, also operated at the full furnace-temperature, but supported and operated in a new and different manner; the provision of a type of roll that can be made of lighter weight and of different types of metal than the rolls of my former patent; the provision of a construction of roll-furnace wherein any defective roll can be replaced with a minimum of interruption to the operation; the provision of a roll-type furnace containing a combination of carrying-rolls and driving-rolls wherein the saving of weight and money effected by the combination shall more than offset the added complication produced by the increased number of the parts; the provision of a roll-type furnace wherein the driving elements are operated at an increased speed and hence operate more smoothly and with less strain; the provision of a roll-type furnace of the type described in which wrought-metal rolls can be employed; while further objects and advantages of the invention will become apparent as the description proceeds.

In the drawings accompanying and forming a part of this application, Fig. 1 is a

vertical longitudinal section through a steel-normalizing furnace containing my improvements; Fig. 2 is a view looking down thereon, partly in plan and partly broken away at different levels; Fig. 3 is a vertical cross section of the furnace shown in Figs. 1 and 2; Fig. 4 is a similar cross-section showing cantilever shafts and other minor modifications; Fig. 5 is an enlarged detail sectional view of one end portion of a dry-shaft assembly; Fig. 6 is a horizontal sectional view of part of the furnace shown in Fig. 4; Fig. 7 is a cross-section of a furnace showing my improvements as applied to a wet shaft assembly; Fig. 8 is a cross section of Fig. 7 on the line 8—8; and Fig. 9 shows another modification.

Such a furnace as herein contemplated comprises an elongated chamber 1 defined ordinarily between a hearth or floor 2, side-walls 3, 3, and roof. The side walls are ordinarily reinforced by vertical metal members 5—5 ordinarily called "buckstays", and the side-walls 3—3 are formed with spaced horizontal apertures 6 for the passage of rotatable shafts 7, provided just inside each side wall of the furnace with a metallic disk or carrying-wheel 8. This shaft may traverse the furnace chamber from side to side as shown in Figs. 2, 3, 5, and 7, or it may be discontinued inside the furnace chamber as shown in Figs. 4 and 6, leaving merely sub-ends as shown at 7^a, although with certain secondary changes in the mode of supporting and driving said shafts as will hereafter be explained. Whether these shafts are continuous or discontinuous, the disks thereon constitute a support for a series of cylindrical, metal, rolls 10—10, the diameter of each roll being sufficiently greater than the distance between the peripheries of adjacent disks to prevent falling therebetween and sufficiently less than the distance between the centers of adjacent disks to avoid interference with the adjacent rolls.

The length of each roll is preferably such as to bring its ends fairly close to the furnace walls although care must be taken to prevent contact therebetween, for which purpose the rolls and disks are formed with suitable in-

terengaging ribs, grooves, or flanges, care also being taken to afford sufficient looseness to enable the necessary thermal expansion which is sometimes rather great.

Many variations of the above mentioned general features are possible, especially as regards the modes of supporting, journaling, driving, etc. In Figs. 2, 3, and 5, horizontal angle irons 12 are bolted to the buckstays and serve to support massive metal bearings 13 in which the shafts are rotated by means of suitable driving devices such as the worm-gears 14 meshing with worms 15 carried by the longitudinal shaft 16. In the form of the invention shown in Figs. 4 and 6 each of the comparatively short shafts 7^a is journaled in two bearings 13^a—13^b located outside of the furnace wall and rigidly supported at different distances therefrom by means of a suitable yoke-member 18.

To preserve the proper relative axial relation between the disks and rolls I have shown several expedients. In Figs. 2 and 3, each roll is provided at one end with a narrow circumferential groove 19 defining a flange 20 and closely receiving one of the disks 8, the opposite end of the roll having a more extended reduced portion or circumferential recess 21 defined by a shoulder 22, the latter being sufficiently spaced from the other disk to enable expansion and contraction. In order to avoid the necessity of having adjacent disks 8—8 strictly in the same plane it is well, when this arrangement is employed, to have adjacent rolls 10 reversed end for end that the grooves 19 come in opposite ends thereof as shown in Fig. 2. Another possible arrangement is to form each end of the roll with a cylindrical reduced portion 21 as shown in Fig. 7 to enable the shoulders thereby defined to fit between the disks 8—8. Another very satisfactory mode is to employ plain cylindrical rolls 10^a devoid of grooves or flanges and to form the disks 8^a with flanges 23 which overlap the ends of these rolls. In this case the flanges 23 are preferably omitted from alternate disks as shown in Fig. 6, since one flange at each end is sufficient guidance for the two rolls which engage the same, and in this way the necessity of locating adjacent disks in the same plane is avoided.

Preferably the shaft 7 or 7^a, and disks 8 or 8^a are made of metallic alloy having a sufficiently high melting point and rigidity under high temperature to enable them to be operated at full furnace temperature, without artificial cooling. Inasmuch as numerous alloys of this nature are well known and on sale on the market I do not consider it necessary to suggest any formula therefor. Any one of numerous expedients can be employed to restrict the conduction of heat along these shafts so as to keep the bearings 15 sufficiently cool for successful operation. To

this end it is desirable to make the end portions of the shaft hollow as shown in Figs. 5 and 6, thus cutting down the cross-section of the metal available for heat conduction; and also to prevent transfer of heat by convection of the furnace gases around the shaft by providing suitable packing 24 around the same, held in place if desired by means of metal plates 25. Convection-flow of heat inside the shaft is ordinarily so limited by the friction of the gas in the bore as not to be troublesome, though this can also be further arrested by a suitable plug 26 of cement or clay or asbestos or other material. In the case of the cantilever shafts shown in Figs. 4 and 6, stoppage of gas flow from the furnace chamber is essential.

With the cantilever type of shaft shown in Figs. 4 and 6 it is ordinarily sufficient to employ a plain cylindrical hollow shaft section, preferably closed at the inner end or at least at some point so as to prevent outflow of furnace gases therethrough. Owing to the fact that the entire load is in every case carried close to the furnace wall, the load carrying portions of the shafts are largely shielded from the furnace heat. Even the shaft 7 traverses the entire furnace chamber, the middle portion thereof has only to carry its own weight and hence can be made comparatively small.

My improvements lend themselves also to use with water-cooled shafts. In Fig. 7 the shaft 7^b is provided at each end with a swivel joint connected to suitable fluid pipes 30—30 by which cooling fluid is passed through the shaft, thus allowing it to be made of common steel if desired. Ordinarily this is undesirable practice both because of the large amount of heat abstracted by the fluid (in case of water often as much as 50% of the entire fuel value), and also objectionable because of the chilling effect on one side of the articles being treated. With the constructions herein shown these objections can be largely overcome by enclosing each of the shafts 7^b in a housing or shield 31 of inverted U-shaped section, resting on the floor 2 of the furnace, the length being such as to fit between the disks 8—8, and the width being such as to clear the rolls themselves.

These rolls are in all cases made of such an alloy as will withstand the full furnace temperature, but owing to their short length, their simplicity, and their freedom from bearing parts, they can be made very light and inexpensive. Furthermore, owing to their simplicity, especially when made plain as shown in Figs. 4 and 5, they can be made of alloys which are too hard to be readily machined, which therefore enables the employment of less expensive compositions or of compositions having increased hardness and rigidity. Furthermore owing to the lack of any direct mechanical connections thereto, any roll

which fails can be almost instantly removed and replaced merely by displacing a section of the furnace roof or side wall, which is preferably made in separate sections 40—40 for this purpose.

5 The rolls may be made either plain surfaced as shown in Figs. 4 and 5 or formed with peripheral projections 32 thereon as shown in Figs. 1, 2, and 3. These projections can be 10 either integral or applied but each is preferably so spaced from one end of the roll as that a recess will be formed at an equal distance from the opposite end so that when two identical rolls are laid side by side and end 15 for end the projections of the one will fall opposite the recesses of the other, thus requiring only one dimension of roll to be maintained. The diameters of the rolls and disks may bear any desired ratio to each other. 20 When it is necessary to provide housings 31 as shown in Figs. 7 and 8, it is necessary to make the disks considerably larger than their shafts and hence sometimes comparable in size to the rolls; but whenever possible it is 25 preferable to make the disks smaller than the rolls, thereby enabling the shafts to be operated at a higher speed, which reduces the mechanical strain thereon and enables a steadier drive.

30 In Fig. 9 I have shown a further modification in which the rolls 10^b are provided at their ends with circular disks 32 which rest directly on the shafts 7, the latter requiring no enlargements, and even permitting a slight 35 reduction in size as shown. These enlargements or disks when employed may be either integral with the shafts or separate therefrom. I prefer to employ at least a slight enlargement as facilitating manufacture and 40 use.

45 It will be apparent from the foregoing that a great many modifications in detail can be made within the scope of my inventive idea and accordingly I do not limit myself in 50 anywise except as specifically recited in my several claims which I desire may be construed each independently of limitations contained in other claims.

Having thus described my invention what 55 I claim is:

1. A metallurgical furnace having apertured side walls, horizontal shafts located in said apertures and journaled outside of said walls, circular disks carried by said shafts 55 close to the side walls, and conveyor rolls eccentric to said shafts carried by said disks in rolling relation.

2. A metallurgical furnace having apertured side walls, a row of shafts having their 60 ends projecting outward through said apertures and journaled outside of said walls, said shafts having circular carrying portions close inside said side walls, and a horizontal conveyor roll having an end received between 65 and supported by the carrying portions of

each adjacent pair of shafts, the diameter of said roll being greater than the distance between the peripheries of adjacent carrying portions.

3. A metallurgical furnace having apertured side walls, horizontal shafts located in said apertures and journaled outside of said walls, circular disks carried by said shafts close to the side walls, conveyor rolls carried by said disks and located wholly outside of the line defined by the shaft axis, whereby the weight of said rolls and of their load is sustained close to the furnace walls and said rolls are readily removable, and means for rotating all of said shafts in the same direction. 70

4. A metallurgical furnace having apertured side walls, a row of shafts having their ends projecting outward through said apertures and journaled outside of said walls, circular disks carried by said shafts close to said side walls, a horizontal conveyor roll having an end received between and supported by each adjacent pair of disks, and means for rotating said shafts opposite to the desired 80 direction of rotation of said rolls. 85

5. A metallurgical furnace having apertured side walls, a row of shafts having their ends projecting outward through said apertures and journaled outside of said walls, circular disks carried by said shafts close to said side walls, a horizontal conveyor roll having an end received between and supported by each adjacent pair of disks, interfitting provision between said rolls and certain of said 90 disks whereby relative axial movement is limited and means for rotating certain of said disks whereby said rolls are rotated. 95

6. In a metallurgical furnace, a series of parallel horizontal conveyor rolls located 100 close together and traversing the furnace chamber from side to side and a series of shafts supporting and rotating said rolls and journaled outside the furnace chamber, said rolls being free from said shafts and readily 105 removable. 110

7. In a metallurgical furnace, a series of parallel horizontal conveyor rolls located close together and traversing the furnace chamber from side to side, and a series of 115 shafts supporting and rotating said rolls and journaled outside the furnace chamber, said shafts being located eccentrically of said rolls but with their axes parallel to the roll axes. 120

8. In a metallurgical furnace, the combination with apertured side walls of shafts projecting through the apertures, said shafts having carrying portions close inside said walls, bearings for said shafts outside said walls, and rolls inside the furnace having 125 their exterior resting on and rotated by said carrying portions.

9. In a metallurgical furnace, the combination with apertured side walls of shafts projecting through the apertures and having cir- 130

- 5 cular carrying portions close inside said walls, bearings for said shafts outside said walls, and rolls inside said furnace, each roll having an end located between and carried by two adjacent shafts whose peripheries are nearer together than the diameter of said roll.
- 10 15. In a furnace, a series of horizontally spaced supporting shafts journaled outside of the furnace on parallel horizontal axes, and projecting through the furnace walls, and a series of load carrying rolls loosely and removably carried by the portion of said shafts inside the furnace. 70
- 10 16. In a furnace, a series of horizontally spaced supporting and driving disks journaled on parallel horizontal axes, and a series of load carrying rolls resting on and supported and operated by said disks, each of said rolls having external peripheral projections adapted to interfit with the projections of adjacent rolls and said projections being spaced unequally from opposite ends of said rolls whereby such interfitting is secured by the making of adjacent rolls identical in measurements and reversing them end for end. 75
- 15 20 25 30 35 40 45 50 55 60 65 70 75 80 85 90 95 100 105 110 115 120 125 130
11. In a metallurgical furnace, the combination with apertured side walls, of horizontal shafts traversing said side walls and projecting from said apertures, bearings for said shafts outside of said side walls, disks carried by said shafts close inside said side walls, hollow rolls of high temperature alloy having in one piece the distance between opposite disks having their ends resting externally on said disks in rolling relation whereby their weight is sustained close to the furnace wall.
12. In a metallurgical furnace, the combination with apertured side walls, of horizontal shafts traversing said side walls and projecting from said apertures, bearings for said shafts outside of said side walls, disks carried by said shafts close inside said side walls, hollow rolls of high temperature alloy having their ends resting externally on said disks whereby their weight is carried close to the furnace walls, and said rolls are rendered readily removable, and means outside the furnace wall for rotating said shafts, said furnace having a sectional removable roof.
13. In a metallurgical furnace, the combination, carrying disks with horizontal axes located close inside the side walls, hollow rolls having cylindrical end portions located between adjacent disks and partly overlapping their upper surfaces in supported relation, said rolls and at least a part of said disks having cooperating shoulders whereby relative endwise movement is limited, and means working through said side walls for supporting and operating said disks.
14. In a furnace, a series of horizontally spaced supporting disks along each side wall journaled upon parallel horizontal axes, at least a part of said disks having flanges at their edges which are nearest the furnace walls, a hollow metal roll having cylindrical portions resting on said disks, the length of said roll being such as to enable it to fit between the flanges of opposite disks, and means working through the side walls for supporting and operating said disks.
15. In a furnace, a series of horizontally spaced supporting disks journaled on parallel horizontal axes, and a series of load carrying rolls carried by said disks, adjacent rolls being identical and each having a peripheral projection at a given distance from one end and a peripheral recess at an equal distance from the opposite end, adjacent rolls being reversed end for end so that the projection of the one shall lie opposite the recess of the other. 90
16. In a metallurgical furnace, the combination with apertured side walls, of horizontal shafts traversing the furnace chamber and having their extremities projecting through said apertures, bearings for said shafts outside of said side walls, disks carried by said shafts close inside said side walls, hollow rolls of high temperature alloy having their ends located between and resting partly upon adjacent disks, and driving means operatively connected to said shafts outside the furnace. 100
17. In a metallurgical furnace, the combination with apertured side walls, of horizontal shafts traversing the furnace chamber and having their extremities projecting through said apertures, bearings for said shafts outside of said side walls, disks carried by said shafts close inside said side walls, hollow rolls of high temperature alloy having their ends located between and resting partly upon adjacent disks and stationary, heat-insulating shields surrounding and protecting the parts of said shafts between the disks thereon. 110
18. In a metallurgical furnace, the combination with apertured side walls, of horizontal shafts traversing the furnace chamber and having their extremities projecting through said apertures, bearings for said shafts outside of said side walls, disks carried by said shafts close inside said side walls, hollow rolls of high temperature alloy having their ends located between and resting partly upon adjacent disks and inverted 120
19. In a metallurgical furnace, the combination with apertured side walls, of horizontal shafts traversing the furnace chamber and having their extremities projecting through said apertures, bearings for said shafts outside of said side walls, disks carried by said shafts close inside said side walls, hollow rolls of high temperature alloy having their ends located between and resting partly upon adjacent disks and stationary, heat-insulating shields surrounding and protecting the parts of said shafts between the disks thereon. 115
20. In a metallurgical furnace, the combination with apertured side walls, of horizontal shafts traversing the furnace chamber and having their extremities projecting through said apertures, bearings for said shafts outside of said side walls, disks carried by said shafts close inside said side walls, hollow rolls of high temperature alloy having their ends located between and resting partly upon adjacent disks and inverted 125

trough-shaped shields surrounding and protecting the parts of said shafts between the disks thereon, said shields supported by the furnace floor.

5 21. In a metallurgical furnace, the combination with apertured side walls, of horizontal hollow shafts traversing the furnace chamber and having their extremities projecting through said apertures, bearings for said shafts outside of said side walls, disks carried by said shafts close inside said side walls, hollow rolls of high temperature alloy having their ends located between and resting partly upon adjacent disks, connections 10 for circulating cooling fluid through said shafts, and stationary heat-resisting shields surrounding and protecting the parts of said shafts between the disks thereon.

22. In a furnace, a series of horizontal 15 load-carrying rolls inside the furnace chamber, disks inside said chamber on and between which said rolls are laid, and means located outside of said chamber for supporting and rotating said disks, the diameter of 20 the disks being less than that of the rolls.

23. The combination with a furnace having apertured side walls and roof of individually removable sections, of supporting disks located in the furnace chamber with 25 their axes parallel and horizontal, load carrying rolls slightly shorter than the distance between said side walls removably carried on the exterior of said disks, and means working through the apertures for supporting and rotating said disks.

24. In a metallurgical furnace, a series of hollow conveyor rolls located side by side in the furnace chamber, and a series of supporting shafts projecting through the furnace wall between and beneath said rolls and supporting said rolls, said shafts journaled outside the furnace wall.

25. In a metallurgical furnace a series of conveyor rolls located side by side in the 40 furnace chamber, a series of supporting shafts located below and outside said rolls and rotating in the opposite direction therefrom, and means working through the furnace wall for supporting and rotating said 45 shafts.

26. In a metallurgical furnace a series of conveyor rolls located side by side in the furnace chamber, a series of supporting shafts 55 journaled outside and projecting through the furnace wall, the exteriors of said rolls resting on said shafts and the furnace chamber having a removable closure portion adjacent each roll.

27. In a furnace, a plurality of horizontal 60 spaced parallel shafts projecting through the furnace wall and journaled outside the same, means rotating all said shafts in one direction, and load conveying members located in 65 the furnace chamber and resting on said

shafts and rotated thereby in the opposite direction.

In testimony whereof I hereunto affix my signature.
